DELIVERY MECHANISM FOR AUTOMATIC MACHINES

Albert Schulze, Leipzig, Germany, assignor to Metallwerk Terna, Quedlinburg/Harz, Germany, a corporation of Germany

Application May 25, 1938, Serial No. 209,925
In Germany February 22, 1938

3 Claims. (Cl. 312—70)

The invention relates to a device for ejecting articles packed in boxes from automatic machines. It is more particularly suitable for so-called fully automatic vending machines, in which the delivery of the articles is effected directly by the insertion of one or more coins. Such automatic machines are known per se for example for the delivery of cigar or cigarette packages. In the existing constructions, however, the delivery of the goods has been to some extent rendered very difficult and troublesome, because it has been necessary first to adjust the package of articles concerned and then to operate the ejecting device by hand. Other automatic machines have already had the object of delivering the article directly after the insertion of the coin in the slot respectively allocated to a package of articles. These known constructions, however, possess the disadvantage that the box situated at the bottom in each case was ejected forwardly by the actuating mechanism and hence it has been necessary to make the casing of correspondingly deep construction or to effect the removal by withdrawable flaps. This disadvantage is obviated by the construction of the delivery device according to the invention. In addition, the construction according to the invention affords the advantage of an extremely simple and reliable actuating mechanism which scarcely causes any trouble. Also, the manufacture of the device according to the invention is hereby rendered substantially more economical.

The accompanying drawings Figures 1 to 5 show a form of construction of the invention, by way of example.

Figure 1 shows the side view of the actuating mechanism.

Figure 2 the front view, and

Figures 3, 4 and 5 show different stages of the delivery of a package.

In the compartment 21 are situated the stacked boxes of cigarettes or the like, the lowest of which is situated in the tilting tray 10, pivoted on the pin 23. Laterally on the compartment, the actuating rod 6 is pivoted to the screw 24, and has a nose 25 and stop pins 22 and 7. It is pulled to the left in Figure 1 by the spring 15. Behind the actuating rod 6 and pivotally supported by the screw 26 on the compartment or in the casing is disposed the latch 8 provided with an adjustable stop screw 27. This latch 8 is pulled by the tension spring 14 or in a similar manner against the pin 28 of the tray 10, thereby holding the latter in normal locked position. Resting loosely on this pin is also the reset lever 9 pivoted on the

screw 29. On the front of the compartment (Figures 1 and 2) the shaft 17 is mounted in the bearings 30 and 31 and carries the retainer 16 which is rigidly secured to a lever arm and adjustable thereon to the box height by means of two adjusting screws 18a, slidably disposed in slot 18b in the retainer arm. Rigidly secured to one end of the shaft 17 is the lever 4 having a pin 5 on its lower rearwardly bent end. Spring 13 normally tends to pull this lever against second last box 20 of the stack so as to support that box at its front edge. Below the tray 10 or the individual trays normally supporting the stack or stacks of articles, runs the common shaft 1 driven by driving means, advantageously an electric motor in the case of fully automatic vending machines. Mounted on this shaft is an eccentrically shaped element 2 for each stack and provided with a stop pin 3 engageable with lever 4. The pin 22 of actuating rod 6 is pressed in the inoperative position against the coin lever 11 pivoted on screw 32 and which serves as a latch for rod 6. The coin lever is held in latching position by the spring 33 and the stop 34. 35 is the coin cup, 12 the chute for the descending coins. Below the coin lever 11 runs the actuating shaft 19 common to all stacks and carrying the switch lever 18 which operates the switching of the motor. This switch lever is engaged by pin 7 of rod 6 when the latter is thrown to the left in Figure 1.

The delivery mechanism is actuated as follows:

Upon the insertion of the appropriate coin, the coin after the usual checking falls from the coin tester through the chute 12 on to the cup 35. The coin lever 11 is thereby pressed down into the dash-dot position, the pin 22 being thereby released. The actuating lever 6 is then drawn into the dashed line position under the influence of the spring 15, thus performing two functions: firstly it strikes against the adjusting screw 27 and hence removes latch 8 from pin 28, so that the tray 10 tilts, and secondly by means of pin 7, it simultaneously throws into the dash-dot position the switch lever 18 which starts the driving motor for example by means of a mercury switch (not shown). The lowermost box of the stack, lying up to this time freely in the tray 10, slides out by its own weight and falls into the article delivery chute (not shown). Thereupon, by means of the eccentric 2 on the shaft 1, turning in the direction of the arrow, the tray is lifted again and is returned to the starting position. At the same time the lever 9 on tray 10 which, during the descent of the tray, in consequence of its pivotal mounting at the point 29, 55

had ridden freely over the nose 25 of the actuating lever 6, is pressed against the lower side of the nose 25 during the upward movement of the tray and thereby moves lever 6 to the right 5 against the latter's spring tension. When lever 9 has arrived above nose 25 simultaneously with the levelling of the tray, the actuating lever 6 is pulled to the left by its spring 15 until arrested at its pin 22 by the projection of the coin lever 11 as shown in Figure 1. In addition, upon the levelling of the tray, the pin 22 again is engaged by latch 8 which for this purpose is bevelled on the lower side and tray 10 is again locked in normal position shown in Figure 1. Upon further 10 rotation of the eccentric 2, the retainer 16 is moved to the right in Figures 1 and 3 when the lever 4 on shaft 17 is actuated by the pin 3. After moving some distance, this lever is released again, so that the lever and retainer 16 15 can spring back due to the tension of spring 13. This retainer has the form shown in Figures 3-5. It has the function, in cooperation with the construction, according to the invention, of the rear ledge of flap 10, of only releasing one box 20 from the stack for delivery in each case. This is achieved as follows:

Before the delivery mechanism is set in operation, the lowest box of the stack has the position shown in Figure 4. Upon the tilting of tray 10, 25 represented in Figure 5, the rear ledge of the tray, which has a nose-shaped cross section and which for this purpose must be of somewhat smaller height than the height of the particular box, engages below the rear edge of the next 30 box of the stack. On the front of the compartment, this next box as mentioned before is held by the projection of the retainer 16. Upon levelling the tray, its nose-shaped ledge returns to its initial position, so that this next box can fall 35 into the tray as shown in Figure 3. The front edge of this box is at the same time released by the moving of the lever 4 and retainer 16 to the right in consequence of the aforescribed action of pin 3 during the rotation of the eccentric 40 plate as also shown in Figure 3. If now retainer 16 springs back into the normal position (Figure 45), the box which has landed on tray 10 is pushed to the left against the rear ledge of the tray and thus into a position (Figure 4) for reliable 50 delivery on the insertion of the next coin.

The construction of the actuating mechanism is not limited to the construction of the individual actuating elements given in Figures 1 to 5. Thus, 55 for example, the individual members, according to the conditions of space, may be arranged further back or even at some other place behind or in front of the stack compartment, and also in general the configuration may be varied as desired while retaining their function according to 60 the invention. The device is intended in the first place for fully automatic vending machines, but of course a hand crank may be provided instead of a motor, or for example, instead of the actuating mechanism being operated directly by the 65 coin, it may be operated by a hand-operated button released by the conventional coin control.

I claim:

1. In a vending machine or the like, including 70 a magazine for a stack of articles to be delivered, a delivery mechanism comprising a tray disposed below said magazine and adapted to contain the article of the stack next to be delivered, a pivotal support for said tray permitting said tray to freely tilt to deliver said article by gravity, means for normally locking said tray in supported posi-

tion, means for initiating the vending operation, means controlled by said initiating means for unlocking said tray at the initiation of the vending operation, a lifting member for returning said tray into locked position, means controlled by said initiating means for actuating said lifting member during the vending operation and after the article has been delivered, a retainer disposed adjacent to the discharge end of said magazine and below the front edge of the article second next in delivery to support said article and the stack at said edge during the tilting of said tray, and means actuated by said lifting member for operating said retainer to release said second next article to drop onto said tray on the latter's return into locked position, said tray having an upwardly extending ledge rearwardly of the tray's pivotal support and normally disposed rearwardly of and below said second article and adapted to swing forwardly 10 into position below the rear edge of said second article when the tray is tilted and the article on the tray is being delivered, for supporting the rear edge of said second article and the stack during the delivery operation of the tray. 15

2. In a vending machine or the like, including 20 a magazine for a stack of articles to be delivered, a delivery mechanism comprising a tray disposed below said magazine and adapted to contain the article of the stack next to be delivered, a pivotal support for said tray permitting said tray to freely tilt to deliver said article by gravity, means for normally locking said tray in supported position, means for initiating the vending operation, an actuating lever and means controlled by said initiating means for actuating said lever at the initiation of the vending operation, said lever engaging and unlocking said tray-locking means, a resetting element pivotally attached to said tray and a cam on said actuating lever engageably disposed with respect to said resetting element for resetting the actuating lever to normal position when the tray is returned into locked position, a lifting member for returning said tray into locked position, means controlled by said initiating means for actuating said lifting member during the vending operation and after the article has been delivered, a retainer disposed adjacent to the discharge end of said magazine and below the front edge of the article second next in delivery to support said article and the stack at said edge during the tilting of said tray, and means actuated by said lifting member for operating said retainer to release said second next article to drop onto said tray on the latter's return into locked position, said tray having an upwardly extending ledge rearwardly of the tray's pivotal support and normally disposed rearwardly of and below said second article and adapted to swing forwardly 25 into position below the rear edge of said next article when the tray is tilted and the article on the tray is being delivered, for supporting the rear edge of said second article and the stack during the delivery operation of the tray. 30

3. In a vending machine or the like, including 35 a magazine for a stack of articles to be delivered, a delivery mechanism comprising a tray disposed below said magazine and adapted to contain the article of the stack next to be delivered, a pivotal support for said tray permitting said tray to freely tilt to deliver said article by gravity, means for normally locking said tray in supported position, means for initiating the vending operation, means controlled by said initiating 40 means for unlocking said tray at the initiation of the vending operation, a lifting member for returning said tray into locked position, means controlled by said initiating means for actuating said lifting member during the vending operation and after the article has been delivered, a retainer disposed adjacent to the discharge end of said magazine and below the front edge of the article second next in delivery to support said article and the stack at said edge during the tilting of said tray, and means actuated by said lifting member for operating said retainer to release said second next article to drop onto said tray on the latter's return into locked position, said tray having an upwardly extending ledge rearwardly of the tray's pivotal support and normally disposed rearwardly of and below said second article and adapted to swing forwardly 45 into position below the rear edge of said next article when the tray is tilted and the article on the tray is being delivered, for supporting the rear edge of said second article and the stack during the delivery operation of the tray. 50

4. In a vending machine or the like, including 55 a magazine for a stack of articles to be delivered, a delivery mechanism comprising a tray disposed below said magazine and adapted to contain the article of the stack next to be delivered, a pivotal support for said tray permitting said tray to freely tilt to deliver said article by gravity, means for normally locking said tray in supported position, means for initiating the vending operation, means controlled by said initiating 60 means for unlocking said tray at the initiation of the vending operation, a lifting member for returning said tray into locked position, means controlled by said initiating means for actuating said lifting member during the vending operation and after the article has been delivered, a retainer disposed adjacent to the discharge end of said magazine and below the front edge of the article second next in delivery to support said article and the stack at said edge during the tilting of said tray, and means actuated by said lifting member for operating said retainer to release said second next article to drop onto said tray on the latter's return into locked position, said tray having an upwardly extending ledge rearwardly of the tray's pivotal support and normally disposed rearwardly of and below said second article and adapted to swing forwardly 65 into position below the rear edge of said next article when the tray is tilted and the article on the tray is being delivered, for supporting the rear edge of said second article and the stack during the delivery operation of the tray. 70

5. In a vending machine or the like, including 75 a magazine for a stack of articles to be delivered, a delivery mechanism comprising a tray disposed below said magazine and adapted to contain the article of the stack next to be delivered, a pivotal support for said tray permitting said tray to freely tilt to deliver said article by gravity, means for normally locking said tray in supported position, means for initiating the vending operation, means controlled by said initiating 80 means for unlocking said tray at the initiation of the vending operation, a lifting member for returning said tray into locked position, means controlled by said initiating means for actuating said lifting member during the vending operation and after the article has been delivered, a retainer disposed adjacent to the discharge end of said magazine and below the front edge of the article second next in delivery to support said article and the stack at said edge during the tilting of said tray, and means actuated by said lifting member for operating said retainer to release said second next article to drop onto said tray on the latter's return into locked position, said tray having an upwardly extending ledge rearwardly of the tray's pivotal support and normally disposed rearwardly of and below said second article and adapted to swing forwardly 85 into position below the rear edge of said next article when the tray is tilted and the article on the tray is being delivered, for supporting the rear edge of said second article and the stack during the delivery operation of the tray. 90

means for unlocking said tray at the initiation of the vending operation, a lifting member for returning said tray into locked position, means controlled by said initiating means for actuating said lifting member during the vending operation and after the article has been delivered, a retainer disposed adjacent to the delivery end of said magazine and below the front edge of the article second next in delivery to support said article and the stack at one edge during the tilting of said tray, means actuated by said lifting member for operating said retainer to release said second next article to drop onto said tray on the latter's return into locked position,

said tray having an upwardly extending ledge rearwardly of the tray's pivotal support and normally disposed rearwardly of and below said second article and adapted to swing forwardly into position below the rear edge of said second article when the tray is tilted and the article on the tray is delivered, for supporting the rear edge of said second article and the stack during the delivery operation of the tray, and a spring for returning said retainer to normal position and for pushing the article dropped onto the locked tray against the rear tray ledge. 5 10

ALBERT SCHULZE.
